UNITED STATES PATENT OFFICE.

GEORGE A. MEAD, OF MANSFIELD, OHIO, ASSIGNOR TO THE OHIO BRASS COMPANY, OF MANSFIELD, OHIO, A CORPORATION OF NEW JERSEY.

ELECTRICAL CONNECTOR.

1,336,475.

Specification of Letters Patent.

Patented Apr. 13, 1920.

Application filed January 5, 1918. Serial No. 210,523.

To all whom it may concern:

Be it known that I, GEORGE A. MEAD, a citizen of the United States, residing at Mansfield, in the county of Richland and 5 State of Ohio, have invented certain new and useful Improvements in Electrical Connectors, of which the following is a specification.

This invention relates to devices used for electrically connecting the adjacent ends of 10 conductors and its most common use is applied to the uniting of rails for the return current of electric railroads and in such case the device is known as a rail bond.

The object of this invention is to produce 15 a rail bond or connector which shall be simple of manufacture, low in manufacturing cost, efficient as to its application, efficient as to its purpose as a conductor of electric current, efficient as to maintenance 20 of contact with the rail or other conductor and meeting certain requirements peculiar to a bond of the type to be applied by a heating flame of high temperature—one requirement being that of proper proportion- 25 ing of the parts.

The form of bond illustrated and described herein is adapted to be attached to the rail or conductor by the use of the oxy-acetylene flame, the oxyhydrogen flame, the 30 flame of the electric arc or other heating flame of high temperature such as 4000° F. and upward.

Figure 1 shows an end elevation view of 35 my improved bond as it is usually positioned on a rail by an attaching metal indicated by the dotted line.

Fig. 2 shows a side elevation of my bond with one terminal in section.

Fig. 3 shows a top plan of the terminal 40 of my bond as shown in Figs. 1 and 2.

Fig. 4 shows a top plan view of a modified form of terminal.

Figs. 5 and 6 show top plan views of an 45 insert piece used in bonds having terminals as shown in Figs. 3 and 4 respectively.

Fig. 7 shows a modification of a terminal for a rail bond and which can be substituted for that shown in Figs. 1 and 2.

A description of my bond and the preferred form is as follows:

The bond consists of a flexible body member (1) which may comprise two cables or one, or it may consist of a plurality of ribbons all of which are common and well

known elements of a rail bond and are usually made of copper although not necessarily so. Upon the ends of the body member are secured terminal members (2) and which I prefer to construct of steel, iron, Monel metal or alloys high in iron. My preference for these metals is on account of their greater affinity for the metal used in securing the bonds to the rail; also on account of reducing the cost and for the reason that they stand the intense heat of the heating flame used in attaching the bond far better than terminals made of copper although copper is not impossible, or even impractical in use.

The terminal (2) as shown in Figs. 1, 2 and 3 is made up of a sleeve portion (3) which may entirely or only partially surround the body member (1), a shelf or projecting ledge (4) which may or may not entirely surround the head portion of the body member, and an insert member (5) which I have found to be of great advantage in the construction of my bond and contributing largely to the success of the objects of the bond as it permits of the use of thin sheet metal which can be formed up around the bond as a terminal and permits of thickening certain portions of the bond which should be thickened to make the bond a success and to meet the peculiar and exacting requirements resulting from the use of a high temperature flame in its application.

In Figs. 1, 2 and 3 the ends of the body member (1) are shown as upset, enlarged, compressed and projecting slightly above the upper face of the shelf member (4).

I have found that a very efficient bond in a great many respects can be constructed by the use of a flexible body cable and a terminal made of sheet steel, iron or Monel metal but I have found that the use of thin sheet material formed up into proper shape will not withstand the intense heat of the directly applied heating flame used in installing the bond. I have also found that to merely double the thickness of the thin sheet material where a thicker section is required is not sufficient and I have also found that to use sheet material which is thick enough, which by doubling would give sufficient thickness to form the shelf (4), will then be too thick to be properly formed up into a terminal which will be neat in appearance

and all that is required. Therefore by using thin material and thickening up such parts as it is advisable to thicken by the use of an insert member (5), I am able to produce a terminal having the required thickness at those points necessary and no more thickness of metal than necessary at points where not required, and can form the terminal out of sheet metal which is formed up 10 as a rule in a stamping press.

In Fig. 3 I show a terminal in which the sleeve portion (3) extends entirely around the body portion but the shelf or ledge (4) extends only part way around and in such 15 a construction I use an insert piece shaped as in Fig. 5. This, however, leaves no insert along one side of the bond terminal and if it is advantageous for any reason to have the insert along all sides or surrounding the 20 faces of the end of the body, it is only necessary to construct the same similar to Fig. 6. The application of an insert according to Fig. 6 is shown in Fig. 4.

It will be readily understood that if it is 25 desired to extend the shelf (4) entirely around the bond that this is possible and well within the scope of my invention, as my invention admits of flexibility.

The insert can be made in several different 30 ways, for instance it might consist of round wire, square wire, rectangular wire and of any size suitable, or it may be made out of a stamping from sheet metal or cast or by thin sheet material folded on itself 35 and of proper shape.

If it is not desired to upset the end of the 40 flexible body (1) but to leave it practically straight and unheaded as shown in Fig. 7 then it is advisable to anchor the terminal 45 to the body (1) and it is also advisable not to do this by squeezing the sleeve (3) onto the body as flexibility at this point is usually inadvisable; hence, my invention can, by proper application as shown in Fig. 7, be used to anchor or secure the terminal (2) 50 to the body (1) by causing the insert to grip the body portion tightly and seat itself into the surface of the body. This point is illustrated by the insert (9) in Fig. 7.

55 While I have described one of the preferred forms of my bond embodying my invention and also shown and described modifications thereof, I do not wish it understood that these are all the modifications or forms in which my invention may be used as will be readily understood by those skilled in the art.

It is quite possible to modify my invention by forcing the two parts of the sleeve 60 of which the shelf is formed tightly together and without an insert and to increase the thickness of this shelf by overlapping it on the outside with a separate piece of material making the increase in thickness by external 65 in place of internal means.

In Fig. 2 a slot is shown indicated by (10) in the sleeve portion of the terminal and this has been found advantageous as a means of producing greater flexibility between the sleeve and the body at this point. 70

I do not wish to be limited to the exact description and drawing herein disclosed but to be limited only by the following claims.

Claims:

1. An electrical connector adapted to be attached by welding, consisting in combining with a flexible body member a shelf secured to and projecting from the body member and adapted to support and retain 80 attaching metal and to be formed up of sheet metal folded back upon itself and a separate member inserted between the folds of the metal composing the shelf, to increase the thickness of the shelf. 85

2. An electrical connector to be attached by welding comprising in combination with a body member a shelf secured to the body member and adapted to support and retain attaching metal and formed up out of sheet 90 metal and having separate means for increasing the thickness of the shelf over and above that produced by the sheet metal of the shelf.

3. An electrical connector to be attached 95 by welding comprising in combination with a flexible body member a shelf secured to the body member and adapted to support and retain attaching metal and formed of sheet metal folded back upon itself and having 100 separate solid means for increasing the thickness of the shelf beyond that produced by the sheet metal of the shelf.

4. A rail bond adapted to be attached by 105 welding, comprising in combination with a body member having a terminal secured thereto, of a shelf projecting from the terminal and adapted to support and retain attaching metal in overlapping relation to the body member, the shelf composed of sheet 110 metal folded back upon itself and forming a space therebetween and an opening adjacent the body member and a solid filling piece inserted in the space between the metal 115 folds of the shelf.

5. An electrical connector as specified in 120 claim 1 and having the separate insert member in engagement with the bond body.

6. An electrical connector as specified in claim 5 in which the shelf projects from the 125 body member in a plane at right angle to the axis of the body.

7. An electrical connector adapted to be attached by welding comprising in combination with a body member, a shelf member projecting from and secured to the body member adjacent the end thereof, and a third member surrounding the exposed parts of the shelf member to increase the size and extent of projection thereof and act as a 130

ledge to catch and support attaching metal thereon in overlapping relation to the end of the body member.

8. An electrical connector to be attached by welding comprising in combination with a flexible body and a sleeve secured thereto, and provided with a hollow shelf projecting therefrom, of a solid metal filler member positioned in the hollow space of the projecting shelf.

9. An electrical connection comprising a flexible body member and a terminal member secured together, the terminal member provided with a transverse opening to receive and retain the body member, the terminal also having a shelf projecting therefrom composed of a plurality of separately

formed parts compressed and compacted together and adapted to catch and retain an attaching metal in overlapping relation to the end of the body member, one of the parts forming the shelf to engage and lock the body to the terminal.

10. An electrical connector comprising in combination a flexible body and a terminal member secured together, the terminal member provided with a slot open at one side and two ends to receive the body member and having a projecting hollow shelf with a solid metal filler member positioned in the hollow space of the projecting shelf.

In testimony whereof I affix my signature.

GEORGE A. MEAD.
